(57) **CLAIM**

We claim the ornamental design for a combination knife sharpener and fire starter, as shown and described.

DESCRIPTION

FIG. 1 is a perspective view of a combination knife sharpener and fire starter showing our new design;

FIG. 2 is a back elevation view thereof;

FIG. 3 is a front elevation thereof;

FIG. 4 is a right-side elevation view thereof;

FIG. 5 is a left-side elevation view thereof;

FIG. 6 is a bottom plan view thereof;

FIG. 7 is a top plan view thereof;

FIG. 8 is a perspective view thereof, showing the combination knife sharpener and fire starter in an open position;

FIG. 9 is a front elevation view thereof; showing the combination knife sharpener and fire starter in an open position;

FIG. 10 is a perspective view thereof, showing the combination knife sharpener and fire starter in use sharpening a knife; and,

FIG. 11 is a perspective view thereof, showing the combination knife sharpener and fire starter in use with sparks from a knife to ignite a fire.

The broken lines showing hands, knife, and sparks are included for the purpose of illustrating environmental structure and form no part of the claimed design.
